Primary Examiner — Sandra S Snapp*Assistant Examiner* — Leisha N Price(74) *Attorney, Agent, or Firm* — Schwabe Williamson & Wyatt, P.C.(57) **CLAIM**

I claim the ornamental design for a chainsaw guide bar body, as shown and described.

DESCRIPTION

FIG. 1 is a perspective view of a chainsaw guide bar body showing my new design in a position of use with a sprocket nose;

FIG. 2 is a top view thereof;

FIG. 3 is a bottom view thereof;

FIG. 4 is a front view thereof;

FIG. 5 is a back view thereof;

FIG. 6 is a right side view thereof;

FIG. 7 is a left side view thereof;

FIG. 8 is a perspective view of the chainsaw guide bar body wherein a portion of the environmental subject matter has been removed for ease of illustration; and,

FIG. 9 is a second perspective view of the chainsaw guide bar body wherein a portion of the environmental subject matter has been removed for ease of illustration.

The dash-dot-dash broken line immediately adjacent to the shaded area defines the bounds of the claimed design and forms no part thereof. The remainder of the broken lines are provided for environmental purposes only and form no part of the claimed design.
